UNITED STATES PATENT OFFICE.

ALMERIN H. LIGHTHALL, OF NEW YORK, N. Y., ASSIGNOR TO HENRY A. MAURER, OF SAME PLACE.

VIADUCT.

SPECIFICATION forming part of Letters Patent No. 633,861, dated September 26, 1899.

Application filed December 19, 1898. Serial No. 699,673. (No model.)

To all whom it may concern:

Be it known that I, ALMERIN H. LIGHTHALL, a citizen of the United States, residing at New York, in the county of New York and State of New York, have invented certain new and useful Improvements in Viaducts; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to viaducts, and it relates particularly to the construction of the floors of such structures.

The object of the invention is to provide a floor for viaducts which shall be so constructed as to present a support for rails or for a concrete or other roadway over which cars or vehicles may pass without producing the objectionable noises incident to passage over viaducts as at present constructed.

Further, the object of the invention is to provide a floor of the kind referred to which will be light and cheap in construction and fireproof throughout.

With these objects in view the invention consists of a floor for viaducts and similar structures consisting of a series of transverse hollow beams or girders, a layer of hollow terra-cotta or the like, and a plastic substance, such as asphalt, interposed between the terra-cotta and the interior of the beams or girders.

Further, the invention consists of a floor for structures of the character referred to consisting of transverse hollow girders having their upper ends open, a layer of hollow terra-cotta or the like arranged in the girders, a plastic substance, such as asphalt, interposed between the terra-cotta and the inner surface of the girders, and a fireproof and waterproof covering for the terra-cotta and the exposed inner surface of the girders.

The invention is illustrated in the accompanying drawings, in which—

Figure 1 is a side elevation of a section of a viaduct having my flooring applied thereto, the form of girder and other parts shown be-

ing adapted for use in supporting the rails of a railway. Fig. 2 is an enlarged end elevation of one of my girder-sections. Fig. 3 is a perspective view of the form of terra-cotta filling employed. Fig. 4 is a perspective view of a covering for the sides of the girders above the terra-cotta filling. Fig. 5 is a sectional view showing the means for draining the upper surface of the girders. Fig. 6 is an end elevation of a girder, showing a modified form of filling whereby the girders are adapted for the support of a roadway. Fig. 7 is a perspective view of a terra-cotta filling for the upper portion of the hollow girder, and Fig. 8 is a perspective view of the support for the filling shown in Fig. 7.

The main body of the floor is composed of hollow girders or troughs A, which are made up of the metal plates a, forming the sides, and similar plates a², forming the bottom, the parts being connected by the angle-pieces a³, secured to the plates by bolts or rivets. Adjacent girders or troughs are connected by plates B, which are connected to the side plates of the troughs by angle-plates b, suitable attached by bolts or rivets b².

The described construction produces a strong and cheap frame for a floor having alternate plane faces and troughs and which may be supported in any suitable way, as by the straps a⁴, attached to the metal beams A'.

As a means of deadening the sound of trains or vehicles passing over the floor I provide a filling of terra-cotta in connection with a plastic substance, as shown. When the floor is designed as a support for railway-tracks, a series of hollow terra-cotta blocks C are placed end to end in the lower portions of the troughs, partially filling the same from end to end, the blocks being so arranged as to form air-passages from one end to the other of the girders.

As a means of retaining the terra-cotta blocks in place and of aiding in the sound-deadening effect desired I interpose between the blocks and the bottom and sides of the troughs a layer D of a suitable material which may readily be introduced in a semi-liquid condition and which will remain plas-

tic. For this purpose I prefer asphalt or a mixture containing a large proportion of this substance.

Each side of the blocks C are provided with 5 indentations c, into which project the lower edges of slabs E of terra-cotta. These slabs are placed, as shown in Fig. 2, to form a covering for the inner side faces of each of the side plates of the troughs, and they are preferably so placed that their meeting edges are not coincident with those of the blocks C. The plastic material extends up between the slabs E and the inner sides of the side plates and forms a union between the two.

15 The surface of the slabs E and the upper surfaces of the blocks C are both coated with a covering of fireproof and waterproof substance in order to avoid injury by combustion or oxidation to the parts of the structure.

In order to provide for the drainage of the gutters formed in the upper portions of the girders, the plastic layer D is somewhat thicker in the bottom of the troughs at the ends 25 thereof than in the middle, thus giving the upper face of the series of blocks a slight incline toward the center. At the depressed portion of the gutters F one or more drain-pipes G are placed, and these discharge into 30 conduits H, extending longitudinally of the bridge and terminating in a suitable discharge.

When the flooring is to be applied to a viaduct over which a roadway passes, I use the 35 construction shown in Fig. 6 of the drawings. In this form the troughs A are provided along their lower sides with slabs I. (Shown particularly in Fig. 8 of the drawings.) These slabs have depressions i in their upper inner faces 40 for the reception of the bottom of blocks J, which have openings j through them, as shown in Fig. 7. In placing the blocks J in position on the slabs I the blocks are so arranged that the openings extend transversely of the girders A.

In the form shown in Fig. 6 a layer K of the plastic material referred to is interposed between the inner faces of the trough and the slabs and blocks.

45 The upper faces of the blocks are level with the plates B, and upon the surface thus formed

may be placed any suitable road-bed—as, for instance, a foundation of concrete L, covered by a dressing M, of asphalt or the like.

Having thus described my invention, what 55 I claim as new, and desire to secure by Letters Patent, is—

1. A floor for viaducts and the like comprising the hollow guides or troughs, arranged with a space between adjacent girders or 60 troughs, a filling of hollow terra-cotta, and a plastic substance interposed between the terra-cotta and the interior of the girders, substantially as described.

2. A floor for viaducts and the like comprising the hollow girders or troughs, hollow terra-cotta blocks arranged in the girders or troughs, the slabs covering the sides of the troughs, and the plastic substance interposed between the blocks and slabs and the girder 70 or trough, substantially as described.

3. A floor for viaducts and the like comprising the hollow girders or troughs, the blocks of terra-cotta, the plastic substance interposed between the blocks and the trough, and 75 a covering of fireproof and waterproof substance, substantially as described.

4. A floor for viaducts and the like comprising the hollow girders or troughs, the hollow blocks of terra-cotta having indentations in 80 their upper edges, the slabs resting in the indentations and covering the sides of the troughs or girders, the plastic substance interposed between the blocks and slabs and the troughs, and the coating of fireproof and 85 waterproof substance, substantially as described.

5. A floor for viaducts and the like comprising the hollow girders or troughs, the hollow blocks of terra-cotta arranged in the girders 90 or troughs, the layer of plastic material interposed between the blocks and the troughs, the layer being thicker at the ends than in the middle of the troughs, and the drain-pipes arranged in the middle of the girders or 95 troughs, substantially as described.

In testimony whereof I affix my signature in presence of two witnesses.

ALMERIN H. LIGHTHALL.
